HENRY E. SMYSER, OF PHILADELPHIA, PENNSYLVANIA, ASSIGNOR TO "WEIKEL AND SMITH SPICE COMPANY."

Letters Patent No. 91,782, dated June 22, 1869.

IMPROVED SPICE-BOX

The Schedule referred to in these Letters Patent and making part of the same.

To all whom it may concern:

Be it known that I, HENRY E. SMYSER, of Philadelphia, Pennsylvania, have invented an Improved Spice-Box; and I do hereby declare the following to be a full, clear, and exact description of the same.

My invention relates to that class of spice-boxes having detachable lids and detachable perforated partitions or disks; and

My improvement consists in providing the said partition with a flange, which bears against the side of the box, and holds the partition in its place without preventing its ready removal.

In order to enable others skilled in the art to make and apply my invention, I will now proceed to describe its construction and operation, reference being had to the accompanying drawing, which forms a part of this specification, and in which—

Figure 1 is a perspective view of my improved spice-box, with the lid detached;

Figure 2, a sectional view of the same, with the perforated disk also detached; and

Figure 3, a sectional view, showing the perforated disk fitted into the box and the lid closed.

A represents a cylindrical sheet-metal box, of the kind in which ground spices, pepper, &c., are generally packed for transportation, and

B is a lid, which fits over the upper edge of the said box in the usual manner.

Within the box, and above the usual beading a, is an annular rib, a', fig. 2, which affords a rest for a perforated disk, C, when the latter is fitted into the box, as seen in fig. 3.

The edges of the disk C are turned up, as best observed in fig. 2, so as to form an annular flange, b, this flange serving to strengthen the disk, and to enable it to be more tightly fitted into its place in the box.

When the lid B of the box is removed, the pepper or other contents can be distributed through the perforations of the disk C, in the quantities required for use, in the same manner as from an ordinary dredge-box with a perforated lid; or, if it be desired to en-

tirely empty the box, or to again fill it after the contents have been used, the perforated disk C can be readily detached, as it is not soldered, but merely fitted tightly into its place.

I am aware that a patent was granted to C. T. Palmer, June 23, 1868, for an improved spice-box having a perforated lid, which was covered by a loose metal plate, held in its place by a paper label, pasted over the lid and top of the box. It has been found, however, that in transporting these boxes, the label frequently becomes torn off, releasing the metal plate, and permitting the contents to be spilled through the perforations of the lid; another objection being that after the label and covering-plate are removed, to obtain a portion of the contents, the remainder are more or less exposed to the air, and lose a portion of their strength before being used.

I am also aware that detachable partitions have been used, the partitions merely resting on the bead, so that they frequently become detached on inverting the box.

These objections are entirely overcome by my invention, the perforated disk permitting the contents to be distributed as they are required for use. The flange b, without preventing the removal of the partition, holds it firmly in its place, even when the box is inverted, while the lid B prevents the spilling of the said contents, and effectually protects the same from exposure.

I claim as my invention, and desire to secure by Letters Patent—

The flange b, arranged on the perforated disk C, when the latter is adapted to an internal rib, a', in the box A, as specified.

In testimony whereof, I have signed my name to this specification, in the presence of two subscribing witnesses.

H. E. SMYSER.
